BED MOTION FOR PRINTING PRESSES

William M. Kelly, Westfield, N. J.; Della Kelly, executrix of said William M. Kelly, deceased

Application June 11, 1947, Serial No. 753,995

16 Claims. (Cl. 74—27)

1

This invention relates to printing presses. More particularly, the invention deals with a simple and economical means for actuating the bed back and forth in the press in a manner to provide a substantially constant operation of the bed in both directions. Still more particularly, the invention deals with a bed motion involving the use of three shaftings, and from this standpoint may be properly termed a tri-shaft bed motion, wherein a minimum number of parts are employed, and further wherein certain of the few parts employed are duplicated. Still more particularly, the invention deals with a bed motion wherein two rotating segments traveling in opposite directions drive the bed at uniform speed on the printing and return idle stroke, and wherein two independently reciprocating bars are employed to actuate oscillating gear segments to reverse the direction of the bed at the end of uniform travel, and further wherein centrally located gear segments are employed to reverse the bed at the end of uniform travel.

The novel features of the invention will be best understood from the following descriptions when taken together with the accompanying drawings in which certain embodiments of the invention are disclosed; and in which the separate parts are designated by suitable reference characters in each of the views; and in which:

Fig. 1 is a side-sectional view diagrammatically outlining a printing press and showing my improved bed motion, the section being substantially on the line 1—1 of Fig. 2, with parts of the construction broken away.

Fig. 2 is a plan view of the press as seen in Fig. 1, omitting the bed and other super-structure, with parts of the construction broken away and in section.

Fig. 3 is a section substantially on the line 3—3 of Fig. 1, with parts of the structure broken away and in section; and

Fig. 4 is a diagrammatic plan view showing the arrangement of racks on the bed, the bed being indicated in part in dot and dash lines.

In bed motions of the general type and kind under consideration, it has been customary to employ rather complicated mechanisms including many shafts, in order to perform the desired operation of the bed, and it is the purpose of my present invention to construct a bed motion for printing presses, wherein only three primary shafts are employed and a minimum number of parts. Here several of the parts are simply duplicates, thus further minimizing the number of individual different parts which are employed.

2

It is further one of the objects of my invention to provide a smooth positive bed motion wherein true harmonic motion is employed in the reversing segments, which take control on the vertical center at the end of uniform travel of the bed.

In illustrating one adaptation of my invention, I have diagrammatically outlined in the accompanying drawing, the frame 10 of a printing press in which is mounted a main drive shaft 11, having at one side of the press, a pulley 13 to be driven by a belt 14 from a suitable drive, for example, an electric motor 15, note Figs. 1 and 2. The frame 10 includes a central longitudinal support 16, and in this support and the sides of the frame are rotatably mounted common single revolution shafts 17—17' which are rotated in reversed directions, the drive of the shaft 17 being from a pinion 18 on the shaft 11, operating upon a large gear 19 on the shaft 17, whereas the shaft 17' is driven through a pinion 20 on the shaft 11, and intermediate gear 21 and a large gear 22 on the shaft 17'. Upper surfaces of the press frame 10 have, as seen in Fig. 3, tracks 23 forming guides for the bed 24 of the press.

In Fig. 1 of the drawing, I have indicated diagrammatically at 25, the printing cylinder, and in dot and dash lines, I have indicated a pinion 26 meshing with the gear 19 and with a gear 27 on the shaft 28 of the cylinder 25, note Fig. 3. The rest of the press structure is not shown as it forms no particular part of my invention, which deals primarily with the bed motion.

Mounted in the center frame 16 is a stub shaft 29, thus completing the third of the tri-shaft construction, comprising the shafts 17—17', the shaft 11 and the stub shaft 29. On the shaft 29, at one side of the frame 16, is a gear 30 which meshes with a pinion 31 on the shaft 11, as will clearly appear in Fig. 1 of the drawing. From this construction, it will be apparent that the shaft 29 rotates two revolutions upon each complete revolution of the shafts 17—17', thereby performing two complete back and forth reciprocations to a pair of oscillating or reciprocating bars 32—32'. The bars 32—32' have elongated apertures 33 in the end portions thereof through which pass studs 34 for guiding the bars in their back and forth reciprocating motion, note Figs. 1 and 2.

Each bar has a downwardly extending elongated loop portion 35—35' in the apertures of which operate crank pins 36—36'. The pin 36' is mounted on the gear 30, whereas the pin 36 is mounted on an enlarged disc 37 at the opposed

end of the shaft 29. The crank pins 36—36' are disposed in opposed relationship to each other, in other words, one hundred and eighty degrees with respect to each other around the shaft 29, as will clearly appear in Fig. 1 of the drawing. In this manner, it will be apparent that as one bar, for example, the bar 32 is moved to the right, the opposed bar 32' is moved to the left. In Fig. 1 they are shown at the extreme of their right and left positions. Upon completing a half turn of the shaft 29, the pin 36 will occupy the position of the pin 36' and vice versa, which would bring the bar 32 to its extreme left position and the bar 32' to its extreme right position.

Driving the shaft 29 at a two-to-one ratio with respect to the shaft 17—17' will result in two complete back and forth strokes of each bar 32—32' upon one revolution of the shaft 17—17'. On the lower surface of each bar is an elongated rack surface 38—38'. These racks are disposed directly over the dual shaft structure 17—17'.

Arranged upon the lower surface of the bed 24 are two similar racks 39—39', these racks being disposed centrally of the bed and outwardly of, or to the outer sides of the bars 32—32'. Arranged on the bed inwardly of said bars and at opposed ends thereof are shorter racks 40—40', the latter racks being also preferably grooved on their inner surfaces, as seen at 41, note Fig. 3, to receive flange portions 42 on the center track 23.

Keyed or pinned to each shaft 17—17', are constantly rotated gear segments or sectors 43—43' substantially of the contour and size seen in the side elevation of Fig. 1, where the segment 43 is shown. In the position of the parts, as seen in the drawing, the segments 43—43' are directly opposed to each other. However, as the shafts 17—17' are operating in reverse directions, it will be understood that at times, the segments will assume different positions circumferentially with respect to the shafts. The segments 43—43' are adapted to operatively engage the racks 39—39' in the travel of the bed back and forth in the press. Assuming that the shaft 17 travels in a clockwise direction and the shaft 17' in a counter-clockwise direction, the segment 43 will move the bed from left to right, whereas the segment 43' moves the bed from right to left. Freely rotatable on each shaft 17—17' are pairs of oscillating gear segments, one segment in each pair comprising a large diameter, but circumferentially short gear segment 44—44' and a radially short and circumferentially long gear segment 45—45', the latter segment being equal to or slightly greater than ninety degrees.

The segments 44—44' are adapted to operatively engage the racks 40—40' respectively, in carrying the bed to the extreme end of the bed stroke and to return the bed to position where the segments 43—43' take-up and complete the drive of the bed in both directions. It will be understood that the segments 44—45, as well as the segments 44'—45' are secured together so that each pair operates in unison. The gear segments 45—45' mesh with the racks 38—38' of the bars 32—32', and thus said bars contribute to the pairs of gear racks the reciprocating or oscillating back and forth motion.

It will be seen from a consideration of Fig. 1 of the drawing that the teeth of the gear segments 43—43' are in mesh with the racks 39—39' while the gear segments 44—44' are still in mesh with their respective racks 40—40', so that at no time will there be any clashing of gears or shift-

ing of motion. The bed will have a continuous drive in both directions.

At this time, it might be well to carry through one cycle of operation of the bed. Starting with the parts in the position shown in Fig. 1, it will be apparent that the gear segment 44 will first operate to move the bed 24 from the delivery end to the left by its engagement with the gear rack 40. In this operation, the bar 32 is moved from right to left through its crank pin 36. During this operation, the segment 43' is brought into operation with the rack 39' in which engagement the bed is continued in its travel to the feeder end of the machine, as seen in Fig. 1. During this motion, the bar 32 will have travelled to the limit of its movement to the left and have started in its return movement to the right.

In the above operation, the bar 32' has been first moved to the right and then to the left, returning the bar 32' to the full line position seen in Fig. 1, which position is assumed by the bar as and when the gear segment 44' has engaged the rack 40', carrying the bed to the extreme limit of its left movement to the feeder end and to then start the return of the bed to the right by again moving the bar 32' to the right through its crank pin 36'. This operation continues until the gear segment 43 engages the rack bar 39 carrying the bed to the right until it is again picked up by the gear segment 44 engaging the rack 40, delivering the bed to the extreme right or delivery end of the machine or back to the position shown in full lines in Fig. 1. As stated before, in the above cycle, each bar 32—32' reciprocates back and forth two times in each complete cycle of operation of the machine. In other words, completes two strokes to the right and two to the left and in one of each of these strokes, the gear segments 44—44' clear the rack bars 40—40' and operate in the blank or central portions of the bed, as will be apparent. It will be understood that the gear segments 45—45' are in constant engagement with the rack teeth 38—38', the latter being sufficiently long on the bars to maintain engagement with the quarter segments 45—45'. The stroke of the bars 32—32' is governed by the crank pins 36—36' and is clearly apparent from a consideration of Fig. 1 of the drawing. It will be apparent that the constantly rotating gear segments or sectors 43—43' by reason of the cutout portions thereof clear the bed racks 39—39' when the latter are at the left and right ends of the press.

Considering the bed drive in a general manner, it may be said that there are two driving mediums or members, each being rotated at a constant speed, one in a direction opposite to that of the other. Each member contributes its definite drive or feed of the bed in a direction consistent with the direction of rotation of the member. With this constant or direct drive is interposed an intermittent drive by oscillating or reciprocating gear segments which continue the drive of the bed in the direction contributed by the first members and then simultaneously returning the bed for delivery or pick-up to the opposed member. In other words, the latter oscillating members may be said to comprise a pair of oscillating members or units which actuate the bed in two directions in contrast to the primary driving members, each of which actuates the bed in one direction, and one in a direction opposed to the other. For actuating the oscillating members, there are a pair of reciprocating bars, positively driv-

ing said members or units and which contribute to each member or unit, two driving motions and two idle motions during each complete cycle of operation of the bed.

In considering the structure of the bed motion, it will appear that the two gear segments 43—43' are identical, as are the gear segments 44—44' and 45—45'. In fact, the gear segments 44—44', as well as the segments 43—43' can actually be segmental portions of gears, similar to the gear 19. This structure together with the three simple shaftings and the few other gears employed, plus the simplicity of the bars 32—32', produces a very simple and economical type of drive and yet a drive which is positive and foolproof in operation. A bed motion of the type and kind under consideration can operate at relatively high speed. It will also be understood that the design of my improved bed motion leaves ample room in the press for other press mechanisms which are commonly employed and which are not shown as they form no part of the present invention.

For purposes of description it may be said that the gear segments or sectors 43—43' comprise constantly rotated drive members rotating in opposite directions, whereas the bars 32—32' comprise reciprocating drivers which actuate the bed at extremities of movement thereof and in reversing the bed as well as in delivering the bed to the constantly rotating members. It will be apparent that in the drive of the bed, the ninety or more degree gear segments or sectors 43—43' have a free rotary movement except as and when these sectors operatively engage the racks of the bed and the oscillating gear segments are free to swing beneath the bed, except as and when these segments 44—44' engage the racks 40—40'.

Having fully described my invention, what I claim as new and desire to secure by Letters Patent is:

1. In printing presses, a bed motion comprising two rotating gear segments, means rotating said segments in opposite directions, a pair of bars mounted for reciprocating movement in the press beneath the bed of the press, the bed of the press having a plurality of gear racks, predetermined racks of the bed being engaged by said gear segments in driving the bed in two directions in the press, and oscillating gear segments actuated by said reciprocating bars engaging other gear racks of said bed for reversing the bed at the limit of travel thereof in both directions.

2. In printing presses, a bed motion comprising two rotating gear segments, means rotating said segments in opposite directions, a pair of bars mounted for reciprocating movement in the press beneath the bed of the press, the bed of the press having a plurality of gear racks, predetermined racks of the bed being engaged by said gear segments in driving the bed in two directions in the press, oscillating gear segments actuated by said reciprocating bars engaging other gear racks of said bed for reversing the bed at the limit of travel thereof in both directions, and the arrangement of the racks on the bed and the gear segments one with respect to the other being such as to maintain progressive engagement of the segments with the racks in driving the bed back and forth in the press.

3. In printing presses, a bed motion comprising two rotating gear segments, means rotating said segments in opposite directions, a pair of bars mounted for reciprocating movement in the press

beneath the bed of the press, the bed of the press having a plurality of gear racks, predetermined racks of the bed being engaged by said gear segments in driving the bed in two directions in the press, oscillating gear segments actuated by said reciprocating bars engaging other gear racks of said bed for reversing the bed at the limit of travel thereof in both directions, the arrangement of the racks on the bed and the gear segments one with respect to the other being such as to maintain progressive engagement of the segments with the racks in driving the bed back and forth in the press, and said bars being crank actuated.

4. In printing presses, a bed motion comprising two rotating gear segments, means rotating said segments in opposite directions, a pair of bars mounted for reciprocating movement in the press beneath the bed of the press, the bed of the press having a plurality of gear racks, predetermined racks of the bed being engaged by said gear segments in driving the bed in two directions in the press, oscillating gear segments actuated by said reciprocating bars engaging other gear racks of said bed for reversing the bed at the limit of travel thereof in both directions, the arrangement of the racks on the bed and the gear segments one with respect to the other being such as to maintain progressive engagement of the segments with the racks in driving the bed back and forth in the press, said bars being crank actuated, the oscillating gear segments each including a reciprocating gear segment of substantially ninety degrees, and the bars having rack teeth engaging the reciprocating gear segments in the drive of the oscillating segments by said bars.

5. In printing presses, a bed motion comprising two rotating gear segments, means rotating said segments in opposite directions, a pair of bars mounted for reciprocating movement in the press beneath the bed of the press, the bed of the press having a plurality of gear racks, predetermined racks of the bed being engaged by said gear segments in driving the bed in two directions in the press, oscillating gear segments actuated by said reciprocating bars engaging other gear racks of said bed for reversing the bed at the limit of travel thereof in both directions, the arrangement of the racks on the bed and the gear segments one with respect to the other being such as to maintain progressive engagement of the segments with the racks in driving the bed back and forth in the press, said bars being crank actuated, the oscillating gear segments each including a reciprocating gear segment of substantially ninety degrees, the bars having rack teeth engaging the reciprocating gear segments in the drive of the oscillating segments by said bars, the crank drive of said bars reciprocating the bars back and forth twice during each complete revolution of the rotary gear segments, one bar reversing the bed at one end of the press, and the other bar reversing the bed at the other end of the press.

6. In a machine employing a device mounted for movement back and forth in the frame of the machine, a mechanism for actuating said device, said mechanism comprising two members constantly rotating at a common speed in opposite directions to each other, and operatively engaging said device, one member driving the device in one direction and the other member driving the device in the opposite direction, a pair of reciprocating drivers, means actuated by the drivers 75 engaging the device independent of said members

to drive the device in both directions and reverse the device at the limit of its movement in each direction in the machine, said drivers each comprising a rack bar, crank means for reciprocating the rack bar, and a gear segment actuated by said rack bar.

7. A bed actuating mechanism for printing presses, said mechanism comprising three shaftings, one a main drive shaft, another comprising a pair of axially alined shaftings driven from the drive shaft in opposite directions, and a crank shaft driven from the main drive shaft at a ratio of two-to-one to said pair of reversely rotated shafts, a rotating gear segment fixed to each shaft of said pair, the bed of the press having racks engaged by said gear segments, one segment driving the bed in one direction, the other segment driving the bed in the opposed direction, two pairs of oscillating gear segments freely rotatable on said axially alined shafts, a pair of reciprocating drivers, cranks on said crank shaft for actuating said drivers, said drivers having a gear rack operatively engaging one gear segment in each of said pairs operatively engaging spaced racks on said bed for reversing the bed.

8. A bed actuating mechanism for printing presses, said mechanism comprising three shaftings, one a main drive shaft, another comprising a pair of axially alined shaftings driven from the drive shaft in opposite directions, and a crank shaft driven from the main drive shaft at a ratio of two-to-one to said pair of reversely rotated shafts, a rotating gear segment fixed to each shaft of said pair, the bed of the press having racks engaged by said gear segments, one segment driving the bed in one direction, the other segment driving the bed in the opposed direction, two pairs of oscillating gear segments freely rotatable on said axially alined shafts, a pair of reciprocating drivers, cranks on said crank shaft for actuating said drivers, said drivers having a gear rack operatively engaging one gear segment in each of said pairs operatively engaging spaced racks on said bed for reversing the bed, and means for guiding the drivers in their reciprocating movement in the bed.

9. In printing presses, a bed motion comprising a tri-shaft drive mechanism, one shaft comprising the main drive shaft, another shaft comprising a pair of axially alined independently rotating shaft portions, means coupled with the drive shaft rotating said shaft portions in opposite directions one with respect to the other, and the third shaft comprising a crank shaft, means fixed to the shaft portions for driving the bed of the press in two directions, and means comprising a pair of reciprocating drivers actuated from the crank shaft for intermittently operatively engaging the bed to reverse the bed at the limit of movement thereof in both directions.

10. In printing presses, a bed motion comprising a tri-shaft drive mechanism, one shaft comprising the main drive shaft, another shaft comprising a pair of axially alined independently rotating shaft portions, means coupled with the drive shaft rotating said shaft portions in opposite directions one with respect to the other, and the third shaft comprising a crank shaft, means fixed to the shaft portions for driving the bed of the press in two directions, means comprising a pair of reciprocating drivers actuated from the crank shaft for intermittently operatively engaging the bed to reverse the bed at the limit of movement thereof in both directions, and in delivering the bed to said second named means.

11. In printing presses, a bed motion comprising a tri-shaft drive mechanism, one shaft comprising the main drive shaft, another shaft comprising a pair of axially alined independently rotating shaft portions, means coupled with the drive shaft rotating said shaft portions in opposite directions one with respect to the other, and the third shaft comprising a crank shaft, means fixed to the shaft portions for driving the bed of the press in two directions, means comprising a pair of reciprocating drivers actuated from the crank shaft for intermittently operatively engaging the bed to reverse the bed at the limit of movement thereof in both directions, and said last named means including gear segments operatively engaging spaced racks on said bed.

12. In printing presses, a bed motion comprising a tri-shaft drive mechanism, one shaft comprising the main drive shaft, another shaft comprising a pair of axially alined independently rotating shaft portions, means coupled with the drive shaft rotating said shaft portions in opposite directions one with respect to the other, and the third shaft comprising a crank shaft, means fixed to the shaft portions for driving the bed of the press in two directions, means comprising a pair of reciprocating drivers actuated from the crank shaft for intermittently operatively engaging the bed to reverse the bed at the limit of movement thereof in both directions, and said last named means including gear segments operatively engaging spaced racks on said bed.

13. In printing presses, a bed motion comprising a tri-shaft drive mechanism, one shaft comprising the main drive shaft, another shaft comprising a pair of axially alined independently rotating shaft portions, means coupled with the drive shaft rotating said shaft portions in opposite directions one with respect to the other, and the third shaft comprising a crank shaft, means fixed to the shaft portions for driving the bed of the press in two directions, means comprising a pair of reciprocating drivers actuated from the crank shaft for intermittently operatively engaging the bed to reverse the bed at the limit of movement thereof in both directions, and said last named means including gear segments operatively engaging spaced racks on said bed; and said second named means comprising rotatting gear segments operatively engaging other racks on said bed.

14. In printing presses, a bed, two pairs of gear racks on the bed, two pairs of gear segments, one of said pairs of gear segments being rotated in opposite directions and engaging one pair of racks of the bed in driving the bed in two directions in the press, and means oscillating the other pair of gear segments in operatively engaging the other pair of gear racks of the bed in driving and reversing the bed.

15. In printing presses, a bed, two pairs of gear racks on the bed, two pairs of gear segments, one of said pairs of gear segments being rotated in opposite directions and engaging one pair of racks of the bed in driving the bed in two directions in the press, means oscillating the other pair of gear segments in operatively engaging the other pair of gear racks of the bed in driving and reversing the bed, and said last named pair of gear segments having a free oscillating movement relatively to and independent of the bed in each alternate reciprocating movement thereof.

16. In printing presses, a bed, two pairs of gear

racks on the bed, two pairs of gear segments, one of said pairs of gear segments being rotated in opposite directions and engaging one pair of racks of the bed in driving the bed in two directions in the press, means oscillating the other pair of gear segments in operatively engaging the other pair of gear racks of the bed in driving and reversing the bed, said last named pair of gear segments having a free oscillating movement relatively to and independent of the bed in each alternate reciprocating movement thereof, and said rotary gear segments operatively engaging the first pair of racks during substantially one-quar-

5 ter revolution of each of said rotating gear segments.

WILLIAM M. KELLY.
